UNITED STATES PATENT OFFICE

FRANK J. BARNES, OF ST. LOUIS, MISSOURI

STIFFENER PIN FOR SOFT COLLARS

Application filed October 3, 1932. Serial No. 635,925.

This invention relates to soft collars and particularly to detachable stiffeners for such collars.

An object of the invention is to provide a stiffener pin, adapted for ready insertion in and removal from the front portion of a soft collar, and adapted to be inexpensively formed of wire.

Another object is to provide such a pin with means for securely holding it in its proper position in a collar.

A further object is to form an exposed end of such a pin with a pointed spring fastener, the point whereof may be inserted in the fabric of the collar to hold the pin in place, being resiliently held when so inserted, and readily yieldable to allow a removal of the pin.

These and various other objects the invention attains by the construction herein-after described, and illustrated in the accompanying drawing, wherein:

Fig. 1 is a front view of the top portion of a shirt carrying a soft collar, equipped with a pair of the hereindisclosed stiffener pins, one of the points of said collar being upturned to afford a better showing of the pin stiffening the same.

Fig. 2 is a perspective view of the stiffener pin.

Referring now more particularly to these views, wherein like reference characters designate the various parts, 1 designates a shirt and 2 a soft collar attached thereto, said collar having the usual hem 3 bordering its free edge and stitched against its rear face.

The present invention comprises a pair of pins 4, formed of a stiff and resilient wire, preferably steel, such as piano wire. The lower end of each pin is tapered to a point 5, but preferably not a sharp one. At its upper end, each pin integrally carries an approximately U-shaped latch head 6, laterally projecting from the pin, at substantially a right angle thereto, the spaced arms formed by said head being positioned one above the other, and hence occupying a plane which also includes the body of the pin. The upper of said arms is somewhat shorter than the lower, and is hence terminally spaced a slight distance

from the extended axis of the pin. Said upper arm has a sharply pointed free end portion 7, which is upwardly bent, with preferably a slight inclination toward the extended axis of the pin.

In use of the described stiffener, the end 5 of each pin is pushed through the hem 3 at a point about one half inch below the neck-band 8 of the collar, so that the two pins may be inserted the full length of their body portions within said hems, as the latter approach the two points of the collar. Upon such insertion of each pin, the upper arm of its latch head is swung lightly downward and is released after engaging the point 7 in the fabric of the hem. As said arm regains its normal position, the point 7 penetrates said fabric, so as to positively prevent any accidental escape of the pin from its described position of use. When, however, it becomes necessary to remove the stiffener pins to permit laundering of the collar, or for any other purpose, it is a simple matter to spring the upper arm of the latch head sufficiently downward to disengage the point 7 from the hem.

It will be noted that the head 6, in addition to exercising its latch function, provides a convenient means for gripping the pin during its insertion in or removal from a collar.

This device completely prevents rolling up or wrinkling of the points of a soft collar and insures a neat and symmetrical appearance of said points. It will be applicable, without change of dimensions to all standard sizes of collars, and is completely hidden behind the collar, in use. No special eyelet in the collar hem is required for insertion of said pin, and the perforation formed by its insertion in the hem is so small, as to be hardly perceptible.

The invention is presented as including all such modifications and changes as come within the scope of the following claims.

What I claim is:

1. A collar stiffener comprising a pin insertable at one end in the hem of a collar, and pointed at its other end to engage the collar for holding the pin in inserted posi-

tion, said pin having a spring portion laterally bent and return-bent adjacent to said pointed end for yieldably holding the point in engagement with the collar.

2. A collar stiffener comprising a pin fashioned at one end for insertion into the hem of a collar, and formed at its other end with a point extending in the general direction of said pin for a restraining engagement with the collar, and laterally bent and return-bent adjacent to its pointed end to form upper and lower spaced arms, the upper of said arms terminally carrying said pointed end, in a spaced relation to the extended axis of the pin.

In testimony whereof I sign this specification:

FRANK J. BARNES.
